CRIMPER MECHANISM

John F. Halstead, Brooklyn, N. Y., assignor to
 International Cigar Machinery Company, a
 corporation of New Jersey

Application February 20, 1942, Serial No. 431,613

7 Claims. (Cl. 131—89)

This invention relates to cigar making machines and more particularly to improvements in the cigar shaping mechanism of a cigar machine.

A great deal of force is exerted by a crimper on a cigar bunch in order to impart thereto the shape which the finished cigar is to have. Various structures, such for example as that shown in Halstead 1,729,440 and Bronander 1,578,579, have heretofore been devised capable of exerting the prescribed amount of force. In most cases it was found that the shaft supporting the lower jaw was excessively worn and the strain placed on this shaft in many cases causes it to be broken off in the crimping operation, especially when two cigar bunches happen accidentally to be in the crimper at the same time. In designing modern crimping devices it is desirable to have the jaws close and open along different paths of travel to prevent tearing a cigar bunch, as provided for in applicant's former patent heretofore mentioned.

It is an object of applicant's invention to provide a crimper which will have the above mentioned desirable opening and closing movements and which will also materially reduce undesirable wear upon the crimper operating members.

Another object is to provide an improved crimper which will be of simplified construction and will have adequate protection against foreign matter entering its operating mechanism.

Another object is to provide a simple and compact crimper which will avoid undesirable twisting stresses upon the crimper operating members.

A further object is to provide an improved crimper wherein the physical force lines bringing the crimper jaws together into crimping relation come from diametrically opposed directions and lie in a plane passing through the center of a cigar bunch undergoing crimping.

A further object is to provide an improved crimper wherein the crimping jaws will be locked during the crimping operation and which will avoid placing undesirable stress upon the actuating cam rollers and cam tracks.

Other objects and features of the invention will appear as the description of the particular physical embodiment selected to illustrate the invention progresses.

In the accompanying drawings, which form a part of this specification, like characters of reference have been applied to corresponding parts throughout the several views which make up the drawings, in which:

Fig. 1 is a side view, partly in section, of applicant's crimping mechanism.

Fig. 2 is a front view of the crimper.

Fig. 3 is a top view of the crimper.

Fig. 4 shows the cam mechanism for operating the crimper.

Referring to the drawings, Figs. 1 and 2, a base 10, having upright side supports 11 and a center boss 12, is secured to the frame of a conventional cigar machine by means of suitable clamping bolts 13. A shaft 14 is fixedly secured in the boss 12 by means of a tapered pin 15. A sliding casting 16 having bushings 17 is slidably mounted upon the shaft 14 and supports the lower crimping jaws 18. A sleeve 19 is fixedly mounted on the sliding casting 16 by means of screws 20. The sleeve 19 is so constructed that it covers the shaft 14 at all times and travels on the outside of the boss 12 so that foreign matter is always prevented from coming in contact with the shaft 14, thereby reducing the amount of wear upon one of the main parts of the crimper mechanism. Heretofore no satisfactory and practical way of overcoming this difficulty has been provided in any of the crimpers employed on modern cigar machines. A small hole 21 is formed in the upper part of the casting which communicates with a hole in the upper bushing 17 to permit the entrance and expulsion of air as the casting 16 slides up and down on the shaft 14. A cover plate 22 is provided for keeping foreign matter out of the inside of the casting 16 and away from the shaft 14.

A link 23 is connected to a lug 24, which forms part of casting 16, by means of an eccentric pin 25. A clamp screw 26 is provided at the upper end of link 23 to fixedly secure the same to the eccentric pin 25. Shaft 27 is movably mounted in the side wall supports 11. A bracket 28 is fixedly secured to shaft 27 by means of taper pins 29 and has a swinging movement. The upper crimping jaws are secured to bracket 28 by means of conventional clamp screws 31 and 32. The clamp screw 31 is capable of being moved to the right and to the left in slot 56 so that the crimping jaw may be adjusted to accommodate different length cigar bunches. The trimming knives 43 and 44 hereinafter described are adjustably secured by means of arms 69—70 to shaft 45 so that they can be moved in and out to accommodate themselves to the adjustment of the crimper jaws.

Link 33 is movably mounted upon shaft 27 and is connected to the lower end of link 23 by means of a pin 34 so as to form a toggle therewith and

impart a raising and lowering movement to the sliding casting 16. This toggle arrangement takes up all of the stress during the crimping operation and thereby avoids wearing out the actuating cam rollers and their corresponding cam tracks. The actuating rod 35 having a forked end 36 is connected to an arm 37 of link 33, and through said arm actuates the toggle mechanism for raising and lowering the sliding casting 16. By turning the eccentric 25 it is possible to adjust the distance the sliding casting 16 is raised and lowered and in this way control the amount of squeeze about the cigar bunch ends.

A second actuating rod 38 having a forked end 39 is connected to an arm 40 formed on bracket 28 and imparts swinging movement to said bracket. An extension 41 of arm 37 supporting an adjustable screw 42 serves to impart actuating movement to a pair of knives 43 and 44. The knives 43 and 44 by means of arms 69-70 are adjustably secured to a shaft 45 by clamp screws 65, said shaft 45 being freely mounted in bracket 28. A collar 46 is fixedly mounted upon shaft 45 by means of a clamp screw 47 and has a projecting lug 48. A coil spring 49 is positioned between lug 48 and the upper part 50 of bracket 28 and constantly exerts an outward push upon lug 48. The sleeve or collar 46 carries a second lug 56 (Fig. 1) which limits the outward movement of knives 43 and 44 by coming into engagement with the lower portion 67 (Fig. 1) of bracket 28. The screw 42 acts against lug 48 to impart cutting movement to knives 43 and 44 when the crimping jaws are in closed position so as to cut off the ends of a cigar bunch protruding beyond the closed crimping jaws.

The operation of this device may be briefly described as follows:

When the actuating rods 35 and 38 are in their lower-most position, crimping jaws 18 and 30 will be separated from one another. Conventional carrying fingers (which may be similar to those shown in Clausen re-issue Patent 20,441) will deliver an uncrimped cigar bunch between the crimping jaws 18 and 30. Actuating rod 38 will then slowly move upward until the adjustable screw 51, carried by an arm 52 of bracket 28, strikes against an abutment 53 forming part of the crimpler base 10. In the meantime, the casting 16, by means of actuating rod 35 and toggle mechanism 23 and 33, will be raised upward to grip and crimp the cigar bunch held between said crimping jaws.

As crimping jaws 18 and 30 engage with the cigar bunch, the conventional cigar bunch carrying fingers are gradually withdrawn from engagement with the cigar bunch. The center of pin 34 (Fig. 1) is pushed in the direction of sliding casting 16 until link 23 strikes against stop pin 54 which is mounted in sliding casting 16. When link 23 engages with stop pin 54, the center of pin 34 will have moved a short distance past a center line drawn between the center of pins 25 and 27 so as to have a locking action. It will be noted that the center of pins 25 and 27 is directly in line with the center 55 of the crimped cigar bunch. This direct alignment eliminates torque and undesirable stresses which would otherwise be placed upon shaft 14 during the crimping operation. Heretofore such torque and undesirable stresses have caused breakage of different parts of the crimpler mechanism. As a result, applicant is able to use a much smaller size shaft than has heretofore been possible.

When the crimping jaws 18 and 30 are approaching their closed crimping position, which of course will occur before link 23 has actually engaged with pin 54, the further upward movement of connecting rod 35 will cause screw 42 to engage with lug 48 and actuate cutting knives 43 and 44 to cut off the ends of the cigar bunch which protrude outside of the closed crimping jaws, thereby completing the crimping of the cigar bunch.

At the completion of the crimping operation, a pair of conventional bunch carrying fingers (which may be similar to those shown in U. S. Patent 1,786,608) will descend between the crimping jaws and grip the cigar bunch in a manner well understood by those skilled in the art. Actuating rod 35 then commences to descend and knives 43 and 44 gradually withdraw due to the outward pressing action of coil spring 49. As rod 35 continues its descent, sliding casting 16 is withdrawn downward. Suitable opening and closing movements (similar to those shown in U. S. Patent 1,729,440) is imparted to the crimping jaws so as to avoid tearing a cigar bunch, through connecting rods 35 and 38.

Conventional cam mechanism (which is similar in some respects to that shown in U. S. Patent 1,442,200) is provided for operating the crimpler jaws (Fig. 4). A pair of lever arms 58 and 59 are fulcrumed on shaft 60 and carry cam rollers 61 and 62 respectively. Cam rollers 61 and 62 travel in cam tracks 63 and 64 respectively, which are formed on opposite sides of a cam disk 57. Actuating rods 35 and 38 are pivotally connected to the ends of lever arms 58 and 59 respectively. Cam disk 57 is mounted on a shaft 68 which is driven by suitable means from the main shaft of the cigar machine.

The invention above described may be varied in construction within the scope of the claims, for the particular device selected to illustrate the invention is but one of many concrete embodiments of the same. The invention therefore is not to be restricted to the precise details of the structure shown and described.

What is claimed is:

1. A cigar bunch shaper for a cigar machine comprising, a pair of shaping members, a fixed vertical shaft, a support slidably mounted on said shaft for supporting one of said members, a swinging mount for the other of said members, means for actuating said swinging mount, toggle means including an arm having a stationary pivot, an arm having a pivot connecting it to said support, a pin connecting said arms, the axes of said pivots being arranged in a single plane passing through the center of the cigar bunch undergoing shaping for imparting reciprocatory movement to said sliding support in timed relationship with said swinging mount to bring said shaping members into and out of shaping relationship.

2. A cigar bunch shaping device for a cigar machine comprising, a pair of coacting shaping members adapted to shape individual cigar bunches, a fixed support, means swingably connected to said support for supporting one of said shaping members, a sliding support for the other of said members, a toggle connected to said fixed support and to said sliding support, and means for actuating said toggle and said swinging support to bring said shaping members into and out of bunch shaping relationship, said toggle including an arm pivotally connected to said fixed support, an arm pivotally connected to said slid-

ing support and a pin connecting said arms, the pivotal connections of said arms with said supports being arranged in a single plane passing through the center of the bunch being shaped.

3. A cigar bunch shaping device for a cigar machine comprising, a base; a shaft connected to said base; a shaping member connected to said shaft for swinging movement along a predetermined path of travel; a fixed upright member associated with said base; a second shaping member slidably mounted on said upright member; a toggle connected to said second shaping member by a pin and to said shaft for imparting raising and lowering movement to said second shaping member, said pin and shaft being so constructed and arranged that a straight line passing across their longitudinal centers would pass across substantially the longitudinal center of a cigar undergoing crimping; and means for imparting swinging movement to said first named shaping member to bring it into and out of shaping relationship with said second shaping member to shape cigar bunches.

4. An improved cigar bunch shaper comprising, a base, an upright associated with said base, a casting slidably mounted on said upright, crimpler jaws mounted on said sliding casting, a bracket swingably mounted on said base, another set of crimpler jaws mounted on said bracket adapted and arranged to coact with said first named set of crimpling jaws to shape cigar bunches, a toggle arrangement having the same fulcrum at one end as said bracket for lowering and raising said sliding casting, and actuating mechanism for said bracket and casting constructed and arranged to swing said bracket and slide said casting into and out of bunch shaping relationship.

5. A bunch shaper for a cigar machine comprising, a base, a shaft mounted in said base, a bracket swingably mounted on said shaft, bunch shaping members connected to said bracket, a reciprocating support associated with said base, a second set of bunch shaping members connected to said reciprocating support, said second set of

shaping members being adapted and arranged to coact with the bunch shaping members on said bracket to shape cigar bunches, a lug formed on said reciprocating support, a pair of toggle levers connected to said lug and said shaft for imparting lowering and raising movement to said reciprocating member to shape cigar bunches, said lug connection and shaft being so constructed and arranged as to be in line with each other and a cigar bunch undergoing shaping.

6. A cigar machine crimping device comprising, a shaft; a swinging bracket carrying a set of crimpler jaws mounted on said shaft; a reciprocating member carrying another set of crimpler jaws, constructed and arranged to coact with the crimpling jaws mounted on said bracket to shape cigar bunches; a knee-action toggle having one lever arm connected to said shaft and another lever arm connected to said reciprocating member for actuating said reciprocating member; means for swinging said bracket; and means for actuating the knee of said toggle to cause the crimpler jaws on said reciprocating member to coact with the jaws on said bracket to crimp cigar bunches, said toggle being constructed and arranged to be self locking when placed in crimping position by said knee actuating means.

7. In a cigar machine, the combination in a crimping device for shaping the ends only of a cigar bunch, of a rectilinearly movable member movable in a vertical direction, a crimping jaw mounted on said rectilinearly movable member, a swingable member, a crimping jaw carried by said swingable member, said swingable member and said rectilinearly movable member being arranged to move the jaws supported thereon into crimping relationship upon the end of a cigar bunch, and means for applying a force to said rectilinearly movable member to a portion of said member located in the vertical plane normally occupied by the longitudinal axis of the cigar bunch being crimped, said force having its major component disposed in said plane.
